UNITED STATES PATENT OFFICE.

FEDERICO GUILLERMO DIAGO, OF HABANA, CUBA.

VOTING MACHINE.

Application filed December 3, 1924. Serial No. 753,703.

My invention relates to improvements in voting machines and consists of the constructions, combinations and arrangements herein described and claimed.

5 An object of the invention is to provide a voting machine in which all of the necessary functions are performed by the gravitation of suitably weighted balls.

10 Another object of the invention is to provide a voting machine operating on the principles stated, the mechanism of the machine being so arranged that repeating by the same voter is automatically guarded against.

15 Another object of the invention is to provide a voting machine in which the operating functions are performed by balls dropped at various places designated with the candidates to be voted for, provision being made for 20 locking the machine against the dropping of balls when a straight ticket is voted, or locking the machine against voting for more than one candidate under the various parties represented.

25 Another object of the invention is to provide a voting machine having a plurality of shiftable shuttles, one for each candidate represented, the shuttles in the "straight vote" column being so arranged that the operation of any one will lock all other shuttles 30 in the machine and thereby prevent further voting by one person.

Another object of the invention is to provide a voting machine in which the various 35 votes are kept account of by suitable calculating mechanism.

Other objects and advantages appear in the following specification, reference being had to the accompanying drawings, in which 40 Figure 1 is a perspective view of a portion of a voting booth illustrating the improved machine installed therein.

Figure 2 is a detail perspective view of several of the shiftable shuttles in one of 45 the voting columns, together with the guide by which they are carried.

Figure 3 is a detail perspective view of a portion of one of the mica ribbons and the attached cup into which the voting balls are 50 dropped.

Figure 4 is a cross section taken substantially on the line 4—4 of Figure 1.

Figure 5 is a plan view taken substantially on line 5—5 of Figure 4.

Figure 6 is a longitudinal section taken 55 substantially on the line 6—6 of Figure 4.

Figure 7 is a detail longitudinal section of a portion of the voting machine table, taken substantially on the line 7—7 of Figure 4,

60 Figure 8 is a detail sectional view illustrating how the voting ball is first placed in the trap.

Figure 9 is a detail longitudinal section, on the order of Fig. 7, showing how the shuttle lever shifts the series of shuttles as the ball 65 falls through.

Figure 10 is a detail sectional view on the order of Figure 8 showing how the trap is closed to let the ball drop through the cup.

Figure 11 is a detail section on the line 70 11—11 of Figure 10.

Figure 12 is a plan view of the table illustrating the division into spaces for the various candidates of the various parties.

Figure 13 is a detail perspective view 75 showing how the ribbons may be constructed of glass pieces.

Figure 14 is a perspective view of one of the voting trays.

Figure 15 is a perspective view of an adjoining tray illustrating the bayonet joints 80 by which the trays are connected.

Figure 16 is a perspective view of a shuttle lever.

Figure 17 is a perspective view of the movable platform and its associated parts.

Figure 18 is a diagrammatic perspective view of the registering mechanism.

Figure 19 is a detail perspective view of the grand totalizer.

Figure 20 is a detail perspective of one end of the shuttles.

Figure 21 is a detail perspective view of the registering wheel shutters.

Reference is first made to Figure 1. The principal voting apparatus is installed in a booth 1 which in practice will be of a size and style to suit the particular conditions under which it may be employed. The so-called voting table by which most of the mechanism is carried is extensible to permit adding the representatives of new political parties, and in view of this function of the voting apparatus, it is necessary to make the

booth of such size that the apparatus can be accommodated under all conditions.

- The voting table consists of a plurality of boards or trays 2, 3, 4 and 5 (Fig. 6). 5 These are respectively designated by signs or posters 6 (Fig. 1) to represent the various political parties of the territory in which voting is going on. The various trays have pin and bayonet slot connections so that 10 one or more trays may be added should the formation of one or more political parties occur. For example, one side of the tray 2 (Fig. 14) has headed pins 7 arranged to fit into bayonet slots 8 in the confronting side 15 of the tray 3 (Fig. 15).

It is immaterial that the trays 2, etc. are made of wood. They may be made of metal if desired. Each tray has a plurality of holes 9. These holes are circular so that the 20 voting balls 10 (Fig. 10) may readily be dropped through. A suitable box or container 11 (Fig. 1) carries a supply of the balls, and is within reach of the voter as he enters the booth at the door 12. The last 25 tray has also a rectangular hole 13 (Fig. 20) leading to a suitable box 65 (Fig. 1) through a tube 89 (Fig. 20). This is for the purpose of receiving written ballots for candidates whose names do not appear upon the voting 30 table. Preferably the horizontal row of voting holes above the hole or opening 13 is employed for the reception of ballot balls relating to the stray votes received by the box 65, it being necessary to account for 35 these votes as well as others. The hole 13 is closed from registration with the tube 89 upon sliding of the bottom row of shuttles after dropping a ball to agree with the written ballot.

- 40 Each of the circular holes 9 (Fig. 12) has an adjoining printed legend designating the office and candidate intended to be voted for under a particular party. For example, the Republican party, designated by the sign 6 45 (Fig. 1) is furnished with the voting tray 2, above the upper hole 9 of which there appears the legend "Straight vote" (Fig. 12). In other words, a person dropping a ball into the upper hole 9 thereby designates his 50 intention to vote a straight ticket. The hole 9 next lowest is designated by the legend "President." The name of the candidate is also printed near this hole. The remaining holes are similarly designated, and provision 55 must be made for as many holes as there are possible candidates.

Each of the voting trays carries a plurality of pairs of guides 14; a pair for each hole 9. These guides are intended to abut 60 so as to produce continuous transverse guides (see Fig. 12) when two or more voting trays are fitted together to constitute the voting table. The guides 14 provide passages for ribbons 15 of transparent material. 65 The ribbons may be made of mica, celluloid

or other transparent material, and in the event that it is made of such materials, the edges are preferably bound at 16 (Fig. 3) with leather in order to add strength thereto. In Figure 13 the ribbon is composed of 70 glass slips 66 linked at 67.

The ribbon 15 (Fig. 3) is weighted at each end by a lead or other suitable weight 17 (Fig. 6). It also runs over pulleys 18. The ribbon may be moved back and forth in the 75 passage afforded by the guides 14 (Fig. 12) the weights 17 balancing it in any position to which it may be moved, and holding it in such position until the ribbon is moved again.

A cup 19, carried by the ribbon 15, provides a receptacle into which a voting ball 10 is initially introduced. Each ribbon carries a single cup. The cup may be made of hard rubber but is preferably made of 80 glass. It is fitted over an opening 20 in the ribbon 15, and upon moving the ribbon 15, (using the cup 19 as a handle) until the opening 20 registers with a hole 9 in one of the voting trays a ball 10 may be dropped 85 through.

Upon casting a ballot by means of one of the balls 10 the voter places the ball in the outer spoon-shaped end 21 of a trap 22 which is pivoted at 23 in the opening 24 of 90 the cup 19. He now lifts the trap with a finger, causing the ball to roll inside of the cup and at the same time closing the opening 24 against the insertion of a second ball.

Situated beneath each one of the holes 9 of the several voting trays is a shuttle 25. The shuttles are preferably made in skeleton formation so that they will be as light as possible. In addition to this they are made of some light material. Operating 100 between the shuttles and traps 22 are springs 68 for the purpose of ejecting a ball in the event that a voter attempts to repeat. The various shuttles are connected in transverse series by links 26 so that all of the 105 shuttles may move as one when actuated by a tripper 27. The shuttles are movable upon the flanges 69 of rails 70 beneath the voting table.

The shuttles 25 have holes 28 which when 110 in registration with the holes 9 as they normally are, permit a ball 10 to drop through into contact with the adjacent tripper 27. Each of the trippers is pivoted at 29 on a mounting that is common to a number of 115 trippers, and when a ball 10 strikes the concave end 30 the tripper is moved on its pivot and an entire series of shuttles 25 is shifted to the left. In this respect the tripper 27 functions as a shuttle lever.

There is one tripper 27 or shuttle lever 120 for each of the shuttles 25 (see Fig. 6). The dropping of a voting ball 10 through any one of the registering holes 9 and 28 in a voting tray and shuttle respectively will 125

cause the rocking of the associated tripper and the movement of the entire shuttle series to the left. In order that this may be accomplished it is necessary to make the 5 voting balls sufficiently heavy to properly actuate the voting mechanism. As stated before, the shuttles are intended to be made of light material. If desired, they may be made of celluloid or mica, properly framed

10 to strengthen them. It is deemed a common expedient to provide ball bearings for the shuttles if such be found necessary.

The aforesaid movement of shuttles occurs in respect to single series only when 15 voting balls are cast for selective votes. For example, dropping a ballot for "President" in the voting tray of the Republican party will cause the shifting to the left of the entire transverse shuttle series underneath the 20 voting table so that all holes 9 for all offices under the other parties will be closed to prevent repeating.

Casting a ballot for the straight ticket under any one of the parties represented 25 will not only close all other straight ticket holes but also all of the holes for selective voting. This is accomplished by a rod 31 (Figs. 5 and 20) carried by the extreme right shuttle 25 of the shuttle series in the 30 upper or straight ticket column. The rod 31 extends horizontally forward behind each of the shuttles at the extreme right of the several series (Fig. 20) so that shifting the shuttles of the upper series to the left carries 35 all of the shuttles to the left, thereby closing all of the voting holes. Others of the shuttles have similar rods 86, and 87 (Fig. 20), each for closing the various other ticket holes in a manner easily understood. The 40 trippers or shuttle levers at the extreme right of the mechanism (Fig. 6) are so arranged that they will not conflict with the rod 31, but at the same time they are capable of operation to shift the selective shuttle 45 series without interfering with the rod 31.

In reference to the pin and bayonet slot manner of connecting the various voting trays, a similar arrangement is adopted for supporting the trays after connection. Al- 50 though the voting mechanism is housed in a booth 1 it is not intended to imply that the mechanism is built in. It preferably consists of a cabinet 35 (Fig. 6) which includes cross members 36 and 37 (Fig. 12) pro- 55 vided with slots 38 into which headed pins 39 at the ends of the trays are fitted. The described manner of connecting and supporting the various trays produces a table structure. The front of the cabinet 35 is closed 60 by a panel 40 (Fig. 1).

Situated mainly within the cabinet 35 is a plurality of tubes 41 each of which has a flared inlet 42 situated beneath a ballot hole so that the ballot or ball may fall there- 65 into upon being discharged by the shuttle

lever 27. The various tubes discharge into a box or other suitable receptacle 43 (Fig. 18) whence they may be taken and reloaded into the container 11. The box 43 is situated outside of the booth 1 in a separate 70 room or compartment in which vote registering mechanism is located. The structure of this mechanism is presently de- scribed.

Formed at the upper extremities of the 75 sides of the cabinet 35 are guides 44 in which a roll-top 45 is movable across the voting table. There is a handle 46 at the forward edge (Fig. 1) permitting the voter to readily push the roll-top back in order 80 to expose the cups 19 for selective voting. The roll-top 45 is of the slatted type commonly seen in desks bearing this name. The guides 44 extend to the rear of the voting machine (Fig. 4) so that the roll-top 85 may be moved completely back.

The length of the roll-top 45 is such that only the cup 19 in the upper straight ticket column is exposed to view when the roll-top is in the forward position. If the voter in- 90 tends to cast a straight ballot he will not be concerned with the roll top at all. But if he desires to cast selective ballots he must throw the roll top back, whereupon the upper column will be concealed and the re- 95 maining columns exposed to view.

Situated in front of the cabinet 35 is a platform 47. The platform is hinged at 48, and the end opposite to the hinges is nor- 100 mally elevated by springs 49 which, how- ever, are depressed when the voter enters the door 12. The corresponding depression of the platform moves an extension 50 and a bracket 51 (Figs. 4, 6 and 17) downward. The ex- 105 tension 50 carries a triangular cam 52. The bracket 51 carries a latch 53. Rods 54 carry the cam 52, and support the cam in such relationship to the shuttles 25 that all of the shuttles are caused to move to the right (presupposing one of the shuttles 110 series to have been moved to the left) upon the release of the platform when the voter walks off and leaves the booth. The rods 54 are pivotally mounted upon the exten- 115 sion 50 as at 55, and the rods are loosely guided in bearings 56. The looseness of the bearing guides compensates for the slight arcuate movement of the pivots 55 when the extension 50 moves up and down.

The latch 53 has a spring pivotal mount- 120 ing 57 upon the extremity of the bracket 51. The latch has a bulge or cam 58 which rides over a cross bar 59 upon brackets 60 in such a manner as to permit the latch to move to the right (Fig. 4) when the platform 47 is 125 depressed and cause it to move to the left when the platform is released. Supposing the platform to be depressed it is easy to see that the latch 53 will assume the dotted line position in Figure 4 at which time the 130

latch will stand in position across the guides 44, so that a keeper 61, carried by the rear edge of the roll top, will engage the latch when the roll top is thrown back as previously stated. The keeper is nothing more than a short straight bar suitably mounted on the roll top.

Provision for the automatic return of the roll top 45 upon release of the platform 47 consists of weights 62 (Fig. 4) which are connected to the roll top by means of cables 63. The cables run over pulleys 64. The roll top 45 is pushed back by the voter, whereupon the weights are lifted. The latch 53 holds the roll top 45 in the rearward position and upon release of the roll top by the latch the weights 62 pull the roll top forward to the original position.

Reference is now made to Figure 18 which is a diagrammatic illustration of enough of the vote registering means to illustrate the intended arrangement. Inasmuch as each of the tubes 41 represents a different candidate it is obviously necessary to supply each of the tubes with a registering mechanism so that individual ballots may readily be accounted for. Only three of the tubes 41 are illustrated, and consequently only three registering mechanisms are shown. Inasmuch as the construction and operation of each is alike, the description of one will suffice for all.

Situated at the mouth of the tube 41 is a rocker 71 upon which the ballot ball 10 falls, causing a movement of the rocker upon the common pivot 72 before the ball falls into the box 43. This movement of the rocker is transmitted to a rod 73 which extends upward into connection with a dog 74 on the shaft 75. The dog carries a pivoted heel 76 for the purpose of engaging pins 77 on the first registering wheel 78.

This wheel also has a single pin 79 which is engageable with a second dog 80 provided with a pivoted heel 81 for the purpose of engaging pins 82 of a second registering wheel 83. The shaft 75 of the registering wheels is mounted in a bracket 84 which, in turn is suitably affixed to the wall 50 of the compartment in which the registering mechanism is located. This compartment should necessarily be inaccessible to all excepting those who are in authority.

It is to be noted that the wheels 78 and 83 are numbered. The numerals on the wheel 78 run from 0 to 99 and when the 100th movement of the wheel 78 occurs the pin 79 actuates the dog 80 to give the wheel 83 a turn. The numerals on the second wheel 83 run from 0 to 10,000, and if desired, additional wheels may be provided. A grand totalizer 88 (Fig. 19) provides for the count of the total number of votes cast. Operation thereof is caused by upward extensions of the rods 73, or other suitable means.

The operation is readily understood from the following additional description. Refer first to Figure 1. The voter enters the door 12 and steps upon the platform 47. This act depresses the platform because of its movable mounting at the hinges 48 and its yieldable support by the springs 49. The depression of the platform moves the triangular cam 52 downward from the position in Figure 6 to the positions in Figures 7 and 9. This makes room for a movement to the left of any one of the shuttle series 25. The depression of the platform also moves the latch 53 downward so that it assumes the dotted line position in Fig. 4 in readiness to catch and hold the roll top 45.

Upon entering the booth 1 the voter finds the roll top 45 drawn forward (Figs. 1 and 4), concealing all of the voting columns excepting the uppermost one. The reader must bear in mind that the so-called voting columns run crosswise of the voting table, that is to say with the movable ribbons 15. The uppermost voting column is used when the voter desires to cast a ballot for a straight ticket, or in other words he votes for all of the candidates listed for the various offices under one political party.

Assume that the voter casts a ballot for the straight ticket of the Republican party. Inasmuch as the straight ticket column is already exposed it is unnecessary that he touch the roll top 45 at all. The cup 19 is moved to the left until it registers with the hole 9 of the tray 2. The cup 19 is attached to the ribbon 15, and the ribbon moves over the rollers 18 as it is slid to the left, the cup being used as a handle. All other holes 9 are covered by the ribbon.

A ball 10 is now placed in the spoon-shaped end 21 of the trap 22. The inner part of the trap closes the passage of the cup. The spoon-shaped end of the trap is now lifted with one finger, and when the opening 24 is closed, (Fig. 10) the cup passage 110 will have become fully opened so that the ball 10 may pass through. The holes 9 and 28 of the tray 2 and shuttle 25 (Fig. 6) are intended to be in normal registration.

As soon as the ball 10 strikes the concaved end 30 of the shuttle lever or tripper 27 beneath said registering hole (Fig. 7) a rocking of the shuttle lever occurs (Fig. 9) causing the entire series of shuttles 25 of the upper voting column to move to the left and permitting the ball 10 to discharge into the tube 41 therebeneath. The ball ultimately finds its way into the box 43 (Fig. 18). The extreme right shuttle 25 in the upper column carries the rod 31 which has contact with the right shuttle in each of the other shuttle rows or series. The foregoing movement to the left of the upper row of shuttles therefor causes all of the shuttles to move to the left.

This concerted movement of all of the shuttles causes the closure of all of the holes 9 so that after one ballot has been cast in the upper or straight ticket column the entire voting table is closed against the casting of more ballots until after the voter has left the booth. In moving over, as stated, the shuttles at the left will engage the triangular cam 52 (Fig. 9).

10 Should the voter desire to cast selective ballots for the various candidates he must push the roll top 45 back until it is caught and held by the latch 53. This is done against the pressure of the weights 62. The 15 roll top 45 is so designed that when pushed back it conceals the upper voting column. All other voting columns are then accessible for selective voting.

To cast a ballot for president under the 20 Republican party the voter moves the cup 19 in the second column until it comes into registration with the holes 9 of the tray 2. The former cycle of operation is then repeated. The passage of a voting ball 10 into 25 the tube 41 beneath said hole causes the entire shuttle series of the second voting column to be moved to the left so that all shuttle holes are closed in that column. The same procedure is gone through in respect to 30 each of the candidates represented. The casting of a ballot in a particular column closes the ball passage under each party in the same column.

Having cast his ballot or ballots the voter 35 leaves the booth. The release of the platform 47 permits springs 49 to move the triangular cam 52 upward. The action of the cam against the nearest shuttles 25 causes all shuttle series which may have been moved 40 over to the left to be moved toward the right into the original position. Similarly, release of the platform 47 causes the latch 53 to be moved away from the keeper 61 of the roll top 45 so that the weights 62 of the 45 latter may be free to return the roll top to the original forward position. The action of the cam 58 of the latch 53 causes the cam to disengage from the keeper.

In speaking of the passage of the ball 10 into the tube 41 (Fig. 9) mention must also 50 be made that before the ball actually reaches the box 43 (Fig. 18) it first actuates the rocker 71 to in turn operate the register associated with that particular tube. It 55 must also be repeated that the spring 68 associated with each trap and voting cup tends to push the cup to an open position so that there may be no interference with the 60 operation of the machine by sticking of the cup.

Reference is next made to Figure 21. This 65 illustration is largely diagrammatic, the operating details of the various registering wheels 78, 83 and of the grand totalizer 88 being omitted. Situated in front of each

of the registering units is a light shutter 90. In each case the shutter is carried by a crank rod 91 extended to be journaled upon suitable supports, all of the rods being connected by a common link 92.

A lever 93 is intended to engage beneath the lowermost cranked rod 91 and upon depression of the platform 47 by the voter in entering the booth, a resulting rocking of the lever causes all of the cranked rods to 75 turn in unison, moving the shutters 90 upward and concealing the individual registering units. This action is performed by a rod 94 which extends rigidly from the free and movable end 50 of the platform 47 and has a link 95 by which connection is made to the pivoted lever 93. In explanation of the purpose of the arrangement in Figure 21 it must be remembered that publicity of 80 the ballot results is desired but that, at the same time, it is desired to keep such results from the immediate voter as he enters the booth. Upon that occasion it is intended that the shutters 90 shall move up and conceal the registering wheels, but when he 85 emerges from the booth the shutters return to the normal positions, rendering the wheels visible again.

I claim:

1. A voting machine comprising a table having a row of holes, a series of connected shuttles situated under the table each having a registering hole, a ribbon movable across the table over the row of holes, a cup carried by the ribbon and fitted over an opening in the ribbon, said ribbon being movable until the cup aligns with registering holes, and means including a pivoted lever which is movable by a ball inserted in the cup and dropped through registering holes to shift the shuttle series and move all holes out of registration.

2. A voting machine comprising a table composed of a plurality of trays each having a hole and thereby providing a transverse row of holes, a shuttle situated beneath each tray, each shuttle having a registering hole, means connecting the shuttles thereby providing a transverse series, a ribbon movable transversely of the table over said row of holes, a cup fixed upon the ribbon over an opening therein, said ribbon being movable to permit dropping a ball through any of the registering holes with which the cup may be in alignment, and a lever pivoted beside each of the shuttles and having a portion depressible by the ball to cause a movement of the shuttle series.

3. A voting machine comprising a table having a plurality of holes arranged in rows and constituting transverse voting columns, a series of connected shuttles operable beneath each column, each shuttle having a registering hole, a ribbon slidable over each column, a cup fastened to each ribbon over

an opening therein, said ribbon being movable by means of the cup to bring the opening in the moved ribbon into alignment with registering holes to permit dropping a voting ball through, and means for shifting all of the shuttles upon dropping a ball through a pair of holes in a predetermined column to thereby move all of the shuttle holes out of registration.

10 4. A voting machine comprising a table having a plurality of holes arranged in rows and constituting transverse voting columns, a series of connected shuttles operable beneath each column, each shuttle having a 15 registering hole, a ribbon slidable over each column, a cup fastened to each ribbon over an opening therein, said ribbon being movable by means of the cup to bring the opening in the moved ribbon into alignment with 20 registering holes to permit dropping a voting ball through, and means associated with each one of the shuttles causing an entire shuttle series to shift upon dropping a ball through a pair of registering holes thereby 25 moving the shuttle holes of the corresponding columns out of registration with the holes in the table.

5. A voting machine comprising a plurality of trays, each having a hole, means for 30 fastening the trays together to compose a table, said holes then being arranged in a row, a pair of guides carried by each tray being arranged to abut when the trays are fitted together to provide a continuous guide, 35 a ribbon slidable in said guide, weights at the ends of the ribbon keeping it taut and maintaining the ribbon in any adjusted position, a cup affixed to the ribbon over an opening therein, said opening being movable into alignment with any one of the holes upon sliding the ribbon, said ribbon closing all other holes, a series of connected shuttles situated beneath the table each shuttle having a hole registerable with one in the 40 trays, means including ribs and grooves on the trays and in the shuttles, respectively, providing a continuous guide upon which the shuttles are slid able, and means including a shuttle lever pivoted adjacent to each 45 of the shuttles, any one of said levers being capable of shifting the entire series upon dropping a ball into the cup and through said holes and into contact with a portion of the lever.

55 6. A voting machine comprising a plurality of trays each having a plurality of holes, means by which the trays are fitted together to compose a table, said holes then being arranged in transverse rows, means by which 60 the table is supported at the extremities of the trays, a plurality of shuttles each having a hole there being one shuttle for each of the holes in said trays, links connecting said shuttles in rows to agree with the rows 65 of holes in the table, a shuttle lever for each

shuttle, rods running lengthwise of the trays upon each of which a plurality of said levers are pivotally mounted, a ribbon for each of the rows of holes, means carried by each of the trays providing guides for the various 70 ribbons, and a cup fixed over an opening in each of the ribbons for receiving a voting ball when a particular cup is moved into alignment with a registering pair of holes, said ball moving the associated lever to in 75 turn shift an entire shuttle series and move the holes in that row out of registration.

7. A voting machine comprising a table having a column of "straight vote" holes and a plurality of columns of "selective vote" 80 holes, a roll top normally covering all of the holes excepting those in the first column, a latch in a normally inoperative position, a keeper carried by the roll top, a platform in position to be depressed by a voter upon approaching the table, and means for then throwing the latch into an operative position to catch the keeper when the roll top is thrown back to expose the "selective vote" 85 holes and conceal the "straight vote" 90 holes.

8. A voting machine comprising a table having a column of "straight vote" holes and a plurality of columns of "selective vote" 95 holes, a roll top normally covering all of the holes excepting those in the first column, a latch in a normally inoperative position, a keeper carried by the roll top, a platform in position to be depressed by a voter upon approaching the table, means for then throwing the latch into an operative position to catch the keeper when the roll top is thrown back to expose the "selective vote" holes and conceal the "straight vote" holes, means for 100 causing the disengagement of the latch from the keeper upon release of the platform as when the voter steps off, and means including a weight connected with the roll top for returning it to the original position.

9. A voting machine comprising a cabinet 110 having a guide at each side, a table situated within the cabinet having a column of "straight vote" holes and a plurality of "selective vote" holes, a roll top mounted in the side guides, a weight connected with the 115 roll top normally holding it in a forward position to conceal all but the column of "straight vote" holes, a keeper on the roll top, a cross bar fixed in position at a place beyond the ends of the guides, a platform arranged in front of the cabinet to be depressed by the feet of a voter, a latch carried by a portion of the platform, and a cam on the latch working against the cross bar so as to permit the movement of the latch into the 120 path of the keeper when the roll top is thrown back to expose the selective vote holes but retract the latch from the keeper when the platform is released.

10. A voting machine comprising a table 130

- having a column of ballot holes, a shuttle beneath the table for each of the holes, each shuttle having a registering hole, means connecting the shuttles, means associated with each shuttle for moving the entire series in one direction for non-registration of the holes upon the casting of a ballot into any one of the holes of said column, a platform which is depressed by a voter as he steps into the voting booth, and a cam carried by the platform which moves upward with the platform when released to engage one of the shuttles of said series and move the entire series back into a registering position.
11. A voting machine comprising a table having a column of ballot holes, a series of connected shuttles situated beneath the table and having registering ballot holes, a lever pivoted beside each of the shuttles with a concaved end beneath said holes, a movable platform which is depressed by a voter upon approaching the table, a pivotally mounted triangular cam so situated that the entire shuttle series moves theretoward upon dropping a ballot through any pair of registering ballot holes into contact with the conical end of the particular lever, and means including a spring for returning the platform upon release thereof as when the voter steps off causing such movement of the cam against one of the shuttles as will return the entire series to the former registering position.
12. A voting machine having a table provided with a column of ballot holes, a pair of guides running parallel with said column, a flexible ribbon which is movable in the guides, a cup fixed over an opening in the ribbon, said opening being registerable with one of said ballot holes at a time, said cup also having an opening, a trap pivoted in the cup opening, and an exposed spoon-end on the trap arranged to receive a ballot ball, said spoon-end then being raised to permit the ball to roll into the cup and through said ballot hole.
13. A voting machine comprising a table having a row of holes of which each represents a different candidate, a member of transparent material movable across the table over said holes, and a receptacle in the nature of a cup carried by said member and movable into registration with any one of said holes for the reception of a ball ballot.
14. A voting machine comprising a table having a row of holes of which each represents a different candidate, a transparent member including a plurality of glass slips linked together and being movable across the table over said holes, and a cup carried by one of the slips and being communicable with any one of the holes for the reception of a ball ballot.
15. A voting machine including a plurality of series of movable shuttles said shuttles having ballot holes, means for shifting an entire shuttle series upon dropping a ballot through one of the holes, thereby moving all of the holes in said series out of receiving positions, and means carried by each shuttle series so contacting with others of the shuttle series to cause a bodily shifting movement of all of the series to correspond with the shifting of said first series.
16. A voting machine including a plurality of series of shuttles each shuttle having a ballot hole, means situated beneath each hole individually arranged to shift that series in one shuttle of which a ballot is dropped, and rods carried by one shuttle of each series so contacting with adjacent shuttles as to cause bodily movement of all of the shuttles to move the holes out of ballot receiving position when said first series is shifted.
